CIGARETTE MAKING MACHINE

Walter Everett Melins, Deptford, London,
England

Application March 14, 1932, Serial No. 598,822
In Great Britain March 30, 1931

7 Claims. (Cl. 131—39)

This invention relates to cigarette making machines, and refers more particularly to the tobacco feeding apparatus of such machines, and has for its object to provide a device for automatically supplying uniform quantities of tobacco to the said tobacco feeding apparatus.

The invention consists of a device for automatically supplying uniform quantities of tobacco to the tobacco feeding apparatus of a cigarette making machine, comprising a tobacco container adjacent to the hopper of the feeding apparatus, and means for periodically transferring a quantity of tobacco from the container to the hopper.

The invention will be more particularly described with reference to the accompanying drawing, in which:—

Fig. 1 is a view partly in section of a tobacco feeding apparatus showing the invention applied thereto.

Fig. 2 is a section of Fig. 1 with the parts in a different position.

Fig. 3 is a fragmentary view of a portion of Fig. 1 taken in the direction of the arrow "A".

Fig. 4 is an enlarged view of a portion of Fig. 3. Referring to the drawing, the tobacco feeding apparatus is of a well known type in which a carded roller 1 picks up tobacco from a hopper 2 and delivers it to a combing roller 3 which carries it beneath a brushing roller 4 after which it is removed by a picker roller 5 and showered on to a distributing roller 6.

The tobacco is then picked from the roller 6 by another picker roller 7 and showered into the filling trough 8 of the cigarette making machine.

According to the invention the sides of the hopper are extended away from the feeding roller as shown in Figs. 1 and 2, and a bottom plate 9 is arranged between the two extended sides to form a large container or compartment into which a considerable quantity of tobacco is placed.

The compartment is separated from the normal hopper 2 by suitably shaping of the floor of the compartment which in the present instance is curved as shown in Figs. 1 and 2 so that a ridge 10 is formed which separates the compartment from the normal hopper.

A flap 11 is pivoted to the sides of the hopper on a spindle 12 and forms the rear wall of the compartment. This wall is periodically oscillated by suitable mechanism to sweep part of the mass of tobacco contained in the compartment over the ridge 10. The mechanism for operating the flap which is shown on the drawing comprises a revolving arm 13 driven by reduction gearing in

the gear box 14, and is arranged to contact with an arm 15 pivoted at 16. The arm 15 has a further arm 17 fixed thereto and the movement of the arm 15 is communicated to the spindle 12 through link 18 and lever 19. A stop screw 20 prevents lever 15 from falling below a fixed point. As the arm 13 revolves in the direction of the arrow once every two minutes (for example) the arm 15 is lifted and the flap 11 is moved into the position shown in Fig. 2. As the mechanism falls back when the roller on arm 13 passes the point of the lever 15, a dash pot 21 prevents the parts from falling too rapidly, and thus avoids shock or noise.

When the tobacco in the compartment is swept into the hopper, the latter takes as much tobacco as it requires and the surplus falls back into the compartment as the flap recedes, it being understood that the tobacco in the flap will pull back a certain amount from the hopper owing to the fact that the strands of tobacco are tangled with one another. The flap 11 may also be operated manually by pushing on it or on the levers and links to facilitate the filling of the normal hopper when starting up the machine or for other emergencies.

In order to assist in dividing the tobacco when the flap 11 falls back to its ordinary position so that the tobacco still contained in the flap will easily separate from that portion of the tobacco which is swept into the hopper, the ridge 10 may have a separating device 22 fitted thereto. The separating device preferably comprises a coarsely threaded rod which does not rotate, but is carried on springs 23 and is rapidly vibrated endwise by a cam 24. An additional spring 25 which may easily be changed is provided for the purpose of adjustment.

It is found that when the rod is oscillated, it separates the tobacco immediately above the ridge and permits some to remain in the hopper and the remainder to fall back into the container.

In some cases a pronged member 25^a, adjustable on a quadrant 26 may be fitted to prevent too much of the tobacco in the container tumbling into the hopper as flap 11 rises. By adjusting the pronged member the quantity of tobacco transferred at each movement of flap 11 may be regulated.

The invention is of course, applicable to types of tobacco feeding apparatus other than the one mentioned.

By the use of the above apparatus the tobacco is kept at a satisfactory level in the normal hopper, and the operator merely has to fill the con-

tainer from time to time and is relieved from the necessity of spreading and distributing the tobacco in the hopper as has hitherto been usual.

What I claim as my invention and desire to secure by Letters Patent is:—

- 5 1. In a cigarette making machine, the combination with a feed hopper, of a tobacco supply container located adjacent the feed hopper, and a swinging flap for thrusting tobacco directly from the supply container into the hopper.
- 10 2. In a cigarette making machine, the combination with a feed hopper, of a tobacco supply container located adjacent the feed hopper, and a reciprocating element movable periodically to transfer tobacco directly from the container into the hopper.
- 15 3. In a cigarette making machine having a filling trough and feeding apparatus for delivering tobacco to the trough, the combination with a feed hopper for delivering tobacco to said apparatus, of a supply container adjacent said hopper, and a reciprocating element driven in timed relation with said feeding apparatus for periodically transferring a quantity of tobacco directly from said container to said hopper.
- 20 4. In a cigarette making machine the combination with a receptacle for tobacco provided with means for separating the same into two compartments serving respectively as a feed hopper and a supply container, of means for moving tobacco in the container toward and across the said separating means, whereby a quantity of tobacco may be delivered to the hopper, and a member provided with prongs disposed adjacent the said separating means to retain the bulk of

the tobacco in the supply container and to regulate the delivery of tobacco.

5. In a cigarette making machine, the combination with a receptacle for tobacco having an inwardly protruding bottom wall forming a partition separating the receptacle into a feed hopper and a supply container, of means movable within said supply container and in close proximity to said bottom wall for thrusting tobacco from the container into the hopper.

85 6. In a cigarette making machine, the combination with a receptacle for tobacco having an inwardly protruding bottom wall forming a partition separating the receptacle into a feed hopper and a supply container, of means movable within said supply container and in close proximity to said bottom wall for thrusting tobacco from the container into the hopper, and a device adjustably positioned adjacent the partition for regulating the quantity of tobacco delivered to the hopper.

90 7. In a cigarette making machine, the combination with a receptacle for tobacco provided with means for separating the same into two compartments serving respectively as a feed hopper and a supply container, of means for moving tobacco in the container toward and across the said separating means, whereby a quantity of tobacco may be delivered to the hopper, an adjustable gate adjacent the said separating means for regulating the delivery of tobacco and means adjacent the said separating means and oscillatable transversely of the direction of movement of the tobacco for facilitating separation of the shreds of tobacco.
